UNITED STATES PATENT OFFICE

2,264,734

SHOE REPAIR LAST

Edward B. Anderson, Chicago, Ill.

Application March 29, 1940, Serial No. 326,575

2 Claims. (CL. 12—123)

The present invention relates to shoe repair lasts and has for its primary object to provide a last which has a rigid vamp fitting portion to which is secured a universally adjustable rear portion.

Heretofore many types of shoe repair lasts have been constructed, but none of them has been of a construction to completely fulfill all of the requirements of a practical repair last.

It is a known fact, that when shoes require repair or need new soles to be attached thereto, the shoes in that condition may have become twisted or warped due to the peculiarity of the gait of the person wearing them, inasmuch as the foot member of a human individual is comprised of a series of universal joints such as the ball of the foot, the arch, the ankle, the knee, as well as the hip joint. In actual walking, different persons subject the joints of the foot and leg to different articulation, and hence the resulting wear on the sole and heel portion of a shoe as well as the original shape of the shoe are distorted in accordance with the function of the combined action of the said universal joints comprising the foot and leg member of a human individual.

Because of this fact, when shoes are brought in for repair, after having been worn, they have become acclimated to the particular gait of a wearer. At the present time, the shoe is mounted on repair lasts which are made to conform with the design, shape, and in accordance with the standard of new shoe manufacture.

Inasmuch, as a shoe, after having been worn, will assume a distorted shape in accordance with the explanation heretofore given, that shoe if placed upon a repair last which is made in conformity to new shoe construction, will tend to straighten the shoe when the shoe and last are placed in the press.

The new sole is thus cemented to the worn shoe, which when taken out of the machine will tend to assume its distorted shape, caused by the wear, which in turn will tend to loosen or detach the sole from the upper portion of the shoe.

After considerable experimenting, I found that a shoe repair last in order to be efficient for the purpose of repairing old and worn shoes, must necessarily be constructed so as to acclimate itself to the shape of the distorted shoe. With this view in mind, I have provided a flexible shank engaging means which is adaptable to various pitches between the shoe sole and the heel seat, and at the same time also adapt itself to any lateral warpage which may have been produced in the shoe thru wear.

Another object of my invention is to provide an effective locking means, for locking the universally flexible shank means in fixed position,

once it has assumed a position congruent with the distorted form of the shoe to be repaired.

Another object of my invention is to provide a shoe repair last of the character to be described, which is simple in construction, practical in use, efficient in operation, and economical to produce in quantity production or manufacture.

Other objects, features, and advantages may become apparent from the ensuing description and the accompanying drawing in which like symbols will be used to designate like parts and in which;

Fig. 1 represents a longitudinal cross-sectional view of my invention inserted in a shoe, the last and shoe placed in a standard shoe press used for this purpose.

Fig. 2 is a transversal cross-sectional view on the line 2—2 of Figure 1.

Fig. 3 is a transversal cross-sectional view on the line 3—3 of Figure 1.

Referring to the drawing, especially Figure 1, the numeral 4 designates a shoe such as is to be repaired with my type of repair last. The shoe comprising generally an upper portion designated 7, a sole portion 6, and a heel portion 5. My invention comprises the elements generally designated 8, 12, 18, and 19.

The member generally designated 8 is comprised of a shoe vamp fitting portion 9 which is shaped approximately as shown having an upper square sectional portion 15 connected to a top ledge member 10. The member 10 is provided with a hole 11 preferably of square section in order to receive the adjustable clamping rod 12 which is also of a square section and is provided with a hemispherical tip portion 23, and a V slotted groove 14. The member 12 floats within the square cavity 11 and when it is desired to fix the same in a certain position longitudinally, the thumb screw 13, which is secured to the ledge portion 10, is caused to move inwardly so that its conical tip portion will clamp the member 12 rigidly in place at any point along the groove 14, the purpose of this operation will be hereinafter described.

The member 8 has at its lower portion 9 a spherical button portion 21, and a spherical recess portion 20, the sole member 19 is provided with a recessed portion to fit the button portion 21, and a button portion to fit within the recess portion 20. The purpose of the portions 20 and 21 and the complementary button and recess portions on the member 19 is for the purpose of allocating the members 19 which are made of varied dimensions to fit the varied sizes of shoes, and are interchangeable with the adapter member designated 8, so that the member 8 may be attached to any one of a series of members 19 which are provided for different lengths of shoes

with different shaped vamps or different widths of soles.

The member 19 has secured thereto the important element of my invention 22, which is made of a flexible and resilient material such as spring steel, or any other suitable material, for fulfilling the requirements called for by my invention.

The member 22 is provided with a bent portion 24 and a further bent portion 25, the portion 25 being suitably countersunk in order to receive the screw 26, whereas the member 8 being suitably tapped in order to receive the screw member 26 by virtue of which the member 22 is secured to the adapter member 8.

In other words, the important element comprising my invention the member 22, is permanently attached to the adapter member whereas the members 19 are the interchangeable members which are used in conjunction with the adapter member 8 in order to specifically fit a certain type of shoe.

Usually shoes are worn down at the heel and this causes a certain distortion to take place in the relationship of the axis of the heel with respect to the plane of the sole of the shoe.

The adapter arrangement when assembled to a suitable sole plate 19 is assembled within the shoe, and the shoe is then placed within the repair machine which comprises a table member 29 mounted on a standard 30 or any suitable mounting means.

The table 29 is provided with a flange portion 31 and a recess 32 which is adapted to receive a resilient member, such as a rubber cushion designated 33, and which is shaped as indicated at 34, the rear portion being built up on an incline in order to fit approximately the configuration of the arch portion of a shoe.

The cushion is of a suitable dimension and shape so as to allow the heel member 5 to clear that portion of the machine which holds the member 33. When the hand wheel 18 is rotated the screw portion 17 which is secured to a tapped hole in the arch 16 of the machine, is brought to bear on the surface 10 of the adapter member which in turn compresses the flexible and resilient rubber member 33, thus bringing an equalized and uniform pressure to all parts of the sole 6 which is being cemented to the upper 7.

The member 22 is provided with an arcuate recess portion 27 and the arcuate sides 28. It can be seen that the rear recessed portion 27 of the member 22 is so shaped as to accommodate a wide range of sizes of shoes. It may be required to have one or more members 22 in order to accommodate the wide variety of sizes of shoes, however, if that should be necessary, the members 22 may be easily interchanged and attached to the adapter 8 by removing the screw member 26 and replacing it with a member 22 of more suitable length and configuration to adapt itself to the specific range of shoe sizes to meet the requirements.

The shoe soles are usually cemented to the uppers and after the cement or composition is applied to the sole and to the upper and they are secured in position, it requires that they be held under pressure in a machine or clamping press such as shown suggestively in the drawing, and comprised of the table member 29, the arch portion 16, and the screw pressure handle member 18.

When the suitable sole plate member 19 is se-

cured or positioned with respect to the adapter 8, the assembly is fitted into the vamp of the shoe. The assembly of the shoe 4, the adapter 8, sole plate 19, and the flexible member 22 are then positioned on the resilient pad 33 in the machine.

The member 22 is thus permitted to equalize itself in position and assume the same shape as the rear portion of the inner sole. The hemispherical portion 23 of the rod 12 is then caused to contact the sole member 22 and locked in place by the screw 13 abutting the groove 14. The member 18 is rotated so as to exert enough pressure until the resilient pad 33 more or less conforms to the configuration and shape of the sole portion.

The member 22 not being under any particular strain while this operation is taking place remains in the same position in which it had been prior to the assembly or cementing of the sole.

One often hears that some people purchasing shoes have to break them in, that is they have to wear them for some time before the shoes assume a more suitable twist or distortion which more or less acclimates them to the particular step or gait of the wearer, and hence with present repair machines the tendency is to bring those shoes from the distorted position back to the original position that they were in when newly purchased, which requires additional breaking in by the wearer, and during the process of such breaking in the sole will become loosened from the upper portion.

If my invention is used, the shoe remains in the form to fit the particular gait of the wearer, and thus is provided a more durable repair to a shoe which thru wear has assumed a certain particular or peculiar distortion.

I believe I have described rather succinctly the nature and importance of my invention and the improvement I have produced in the art of shoe repair and construction.

Altho, I have shown a preferred form of putting my invention to practice, I reserve the right to any and all modifications, improvements, and alterations which come within the scope and spirit of my invention and the purview of the foregoing description; my invention being limited only by the subjoined claims.

Having thus described my invention what I claim as new and desire to secure by Letters Patent is:

1. In a shoe repair last, an adapter member provided with universally equalizing shank means comprising, a shank member made of flexible material secured to said adapter member and provided with a formed portion in close proximity to the end which is secured to the said adapter member, and shank securing means adapted to hold rigidly the said shank means in a fixed position.

2. In a shoe repair last, an adapter member provided with universally equalizing shank means comprising, a shank member made of flexible material secured to the said adapter member and provided with a formed portion in close proximity to the end which is secured to the said adapter member, and shank securing means comprising a rod member slidably attached to the said adapter member and rod engaging means secured to the said adapter member.

EDWARD B. ANDERSON.
